Primary Examiner — Selina Sikder(74) *Attorney, Agent, or Firm* — Patterson Thuente Christensen, P.A.(57) **CLAIM**

The ornamental design for a light emitting diode, as shown and described.

DESCRIPTION

FIG. 1 is a perspective view of a light emitting diode showing the claimed design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1; and,

FIG. 6 is a bottom plan view of FIG. 1, which is a mirror image of the top plan view.

The broken lines are directed to environment and are for illustrative purpose only; the broken lines form no part of the claimed design.
